UNITED STATES PATENT OFFICE.

CARL STEIN, OF STEGER, ILLINOIS, ASSIGNOR TO STEGER & SONS PIANO MANUFACTURING COMPANY, OF STEGER, ILLINOIS, A CORPORATION OF ILLINOIS.

PHONOGRAPH.

1,261,174.

Specification of Letters Patent.

Patented Apr. 2, 1918.

Application filed October 14, 1916. Serial No. 125,535.

To all whom it may concern:

Be it known that I, CARL STEIN, a citizen of the United States, residing at Steger, in the county of Will and State of Illinois, have invented new and useful Improvements in Phonographs, of which the following is a specification, reference being had to the accompanying drawings, forming a part thereof.

10 The purpose of this invention is to provide an improved construction in a phonograph or sound-reproducing instrument, particularly with respect to the amplifying and resonating devices. It consists in the elements and features of construction shown and described, as indicated in the claims.

In the drawings:—

Figure 1 is a vertical section, axial with respect to the vertically-extending member 20 of the sound conduit, of a phonograph embodying the features of this invention, the reproducer and tone arm and the record-carrier being shown in side elevation and conventionally,—that is, without regard to 25 details of construction.

Fig. 2 is a vertical section at the line, 2—2, on Fig. 1.

Fig. 3 is a section at the line, 3—3, on Fig. 1.

30 Fig. 4 is a perspective view of a removable resonating device adapted to be contained in the horn mouth or amplifier.

Fig. 5 is a perspective view of an obtrusive deflecting device, adapted to be positioned at the smaller end of the amplifier 35 or horn mouth terminal of the conduit.

Fig. 6 is a perspective view of a partitioning device employed in the sound conduit at the entrance to the amplifier or resonator.

40 The drawings illustrate a phonograph which in the general features of construction is familiar, comprising a reproducer or sound box, 1, a tone arm, 2, to one end of which the sound box is connected, and which is pivoted at the other end to the upright portion, 3, of the sound conduit. This upright portion, 3, of the conduit is of wood mounted in any convenient manner rigid with the cabinet work or inclosing case, 4, 45 which also supports the remainder of the

sound conduit, comprising the amplifier and resonator. This amplifier and resonator is preferably made of wood constituting a horn mouth tapered widening toward its discharge end, the angle of taper or widening increasing from the smaller to the larger end in both horizontal and vertical dimensions, but more rapidly in the horizontal direction, as may be understood from the drawings; the result being, of course, that in longitudinal outlines, both in vertical and horizontal section, this horn mouth is exteriorly curved concavely. This amplifier is oblong in cross-section at all points of its length, the disparity in the two dimensions, 60 however, increasing from the smaller to the larger end. The horn or amplifier 6, is connected with the upright member, 3, of the conduit by a cylindrical elbow member, 5; whose diameter is substantially unchanged 70 throughout the 90-degree-bend of the elbow. The upper end of the elbow is telescoped into the lower end of the cylindrical upright member, 3, and the lower forwardly-facing end is flanged at 5^a, for securing it to a wooden junction member, 5^b, which connects the elbow with the amplifier. This elbow-connecting member, 5^b, is a wooden block which is rectangular in cross section for fitting within the smaller end of the amplifier, 80 and has a duct from end to end for the sound conduit into the amplifier, said duct being at the portion, 5^c, beyond the cylindrical entrance which fits the lower forward end of the elbow, rectangular in cross-section and 85 tapered widening to the end which opens into the amplifier.

The amplifier, 6, besides being a sound-conductor, is designed to be a resonator,—that is, it is designed not only to amplify 90 the vibrations by its expanding form, but to intensify them by its own responsive vibration. Partly for the purpose of increasing this responsive vibratory action of the amplifier, there is provided a device which is shown in Fig. 6, which is inserted in the vertical portion, 3, of the conduit for partitioning that portion of the conduit into a plurality of longitudinal subdivisions or 95 parallel conduits lying adjacent to the cy- 100

lindrical wall of said member, 3. This device comprises the central hub or axial body, 7^a, and any desired number,—as illustrated, four,—radially extending webs or vanes, 7^b, which make contact with the inner cylindrical surface of the said vertical portion, 3, of the conduit. It will be observed that this device by its central or hub portion excludes the air vibrations from so much of the space, 5 and the remainder of the conduit space in this vertical portion, 3, is divided into separate conduits to which the tone arm transmits the sound vibrations, which blend and coöperate in producing the vibration of the 10 air body through the elbow member, 5, and connecting block, 5^b, and into the amplifier and resonator, 6. It is found that to a certain extent the sound vibrations are clarified by being limited to the smaller or sub-di- 15 vided passages by the device, 7, and this effect continues where the vibrations are somewhat restricted to the outer circumferential portion of the conduit, beyond the part, 3,—that is, in the elbow member, 5, and 20 this is the purpose of the device. Carrying out this purpose still further, and supplementing it,—there is provided in the rectangular tapering portion 5^c, of the cavity of the elbow connecting member, 5^b, there 25 is located a wedge-shaped deflector, 8, which is tapered also, but not to a point, in a plane transverse to that in which it is tapered to an edge as seen in Fig. 5. That is to say, the device is tapered in both direc- 30 tions correspondingly to the taper of the said tapering portion of the cavity, 5^c, its vertical dimension being the full corresponding dimension of said cavity which is oblong at its larger end, though it is circular at the 35 smaller end; the result is that the space in said tapering portion of said tapering cavity is obstructed at the middle portion by said wedge-shaped and tapered deflecting device, 8, leaving equal lateral and separated 40 portions at opposite sides, with the effect of causing the sound vibrations to be transmitted by separate lateral bodies of air, and with a clarification of the vibration somewhat increased beyond what it would be if 45 the central portion were not excluded from the vibrations by said deflecting wedge-shaped device, 8, and with the effect desired, namely, that said clarified vibrations occur in the body of the air adjacent to the lateral 50 walls of the amplifier and resonator, 6, and thereby tend to produce correspondingly clearer vibratory effect upon these walls whose vibration intensifies the vibration of the air body within the resonator. For the 55 purpose, furthermore, of obtaining the full effect of the vibration of these separated air bodies and of each of them in all four transverse directions, there is provided mounted within the amplifier and resonator, 6, at the discharge end of the elbow connect- 60 ing member, 5^b, that is, immediately beyond its wide discharge mouth at the wider end of the deflecting and partitioning device, 8, a resonating device comprising two wooden partitions, 10—10, which are framed together 65 by means of side pieces, 11—11, which fit snugly within the amplifier and resonator, as seen in Fig. 3. These partitions extend in the direction of the greater transverse dimension of the transversely oblong amplifier 70 and resonator, cross-wise of the direction of the edge of the wedge-shaped deflector, 8, and thereby partition off the total space in said narrower end of the amplifier into two volumes at the upper and lower side respectively, as indicated at *a* and *b*. The wedge-shaped deflecting device, 8, extending the greater dimension of its wider end crosswise of the adjacent end of the partitions, 10—10, obstructs the middle portion of the width 80 of each of these volumes contained respectively between the two partitions, 10—10, and between them respectively and the upper and lower walls of the amplifier; and thus by the coöperation of the partition, 10—10, and the deflecting device, 8, the sound vibrations are excluded substantially from the central portion of the volume of the narrower end portion of the amplifier, 6, and limited to volumes adjacent to the 85 four sides at least for the distance along the length of the amplifier through which the partitions, 10—10, extend. The rate of widening of the amplifier in both its transverse dimensions increases rapidly beyond 90 the outer ends of the partitions, 10, permitting the amplification of the sound waves issuing through the four volumes indicated, adjacent the four sides of the amplifier, the sound waves blending as they are amplified 95 in this space and being reinforced by the vibration of the four walls of amplifier and resonator itself, as well as by the vibration of the two partitions, 10—10, with the result that the sound issuing from the wide mouth 100 of the amplifier is stronger and of purer tone, less affected by the blunting or muffling which is noticeable when the sound is projected through a tapering horn mouth in which the entire volume of air therein is put 105 into vibration as a unitary volume.

I claim:

1. In a sound-reproducing device, a sound conduit comprising an amplifier and resonator of which the terminal discharge member is tapered widening at an increasing angle toward the discharge, in combination with resonating partitions rigidly fixed within the narrower less rapidly tapering portion of the amplifier and terminating at a distance back from its wide discharge end.
2. In a sound-reproducing instrument, a sound conduit comprising an amplifier and

resonator having a discharge terminal which
is tapered at the discharge end at a wider
angle in one axial plane and at a narrower
angle in an axial plane transverse to the first,
5 in combination with two partitions located
in the narrower tapering portion of said
terminal extending in planes having the

general direction of the axial plane of wider
taper.

In testimony whereof, I have hereunto set 10
my hand at Steger, Illinois, this 7th day of
October, 1916.

CARL STEIN.
